(57) **CLAIM**

The ornamental design for a head scarf, as shown and described.

DESCRIPTION

FIG. 1 is a front, right, and top perspective view of a head scarf, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is another front, right, and top perspective view of a head scarf when the model wears a headscarf.

The broken line outline of the partial human head figure in FIG. 8 assists in illustrating the claimed design in a position of use, but forms no part of the claimed design. The short broken lines along the interior of the head scarf in FIGS. 4 and 7 depict a boundary line to the claimed design that forms no part of the claimed design.

The appearance of any portion of the article between the symbolic break lines forms no part of the claimed design.
